Primary Examiner — John A Voytek(57) **CLAIM**

The ornamental design for a tire, as shown and described.

DESCRIPTION

FIG. 1 is a perspective view of the tire;
FIG. 2 is a front view of the tire;
FIG. 3 is a right view of the tire;
FIG. 4 is a left view of the tire;
FIG. 5 is an enlarged view of the tire with section lines related to views 6, 7;
FIG. 6 is a first transversal section view of the tire taken along line 6-6; and,
FIG. 7 is a second transversal section view of the tire taken along line 7-7.

The broken lines defining the sidewall and inner bead depict environmental subject matter that forms no part of the claimed design.
